UNITED STATES PATENT OFFICE.

THOMAS BURKHARD, OF BROOKLYN, NEW YORK.

BOTTOM FOR CANS, &c.

SPECIFICATION forming part of Letters Patent No. 317,620, dated May 12, 1885.

Application filed March 5, 1885. (No model.)

To all whom it may concern:

Be it known that I, THOMAS BURKHARD, of Brooklyn, in the county of Kings and State of New York, have invented a new and useful Improvement in Bottoms for Stoves, Cans, and other Cylindric Vessels, of which the following is a specification.

Stoves which are employed by confectioners are usually composed largely of sheet metal, and are subjected to very rough usage. Their bottoms have usually been made of sheet metal, and have been strengthened in various ways by skeleton frames of cast-iron, so as to prevent them from bulging downward and cracking when highly heated by the fire being dumped into the ash-pit and then cooled by reason of water thrown in to quench the fire.

My invention is applicable to the bottoms of such stoves, and is also particularly applicable for the bottoms of ash-cans, milk-cans, and other cylindric vessels which are subjected to rough usage, and in which it is difficult to obtain a firm and secure connection of the bottom with the body of the can or vessel, and to avoid bruising and breaking of such bottom.

The invention consists in novel combinations of parts hereinafter described, and pointed out in the claims.

In the accompanying drawings, Figure 1 represents a vertical section of an ash-can embodying my invention. Fig. 2 is a plan of the cast-metal body or frame on which the sheet-metal bottom is secured, and Fig. 3 is a vertical section of a confectioner's stove.

Similar letters of reference designate corresponding parts in all the figures.

A designates the cylindric body or casing. B designates the sheet-metal bottom fitted thereto, and C designates the cast-metal body or frame on which the bottom and casing are secured. The cast-metal body or frame is here shown as of skeleton form, and is composed of a cylindric portion, c, provided at its base with an outwardly-extending rim or base-flange, c', and the top of which is composed of cross bars or ribs c², thereby forming a light skeleton structure which is well adapted to the purpose. The bottom B is of circular form, and has at its periphery a downwardly-turned rim, b, made of a size to slip snugly over the circular portion c of the frame or body C, and preferably of a depth to extend downward upon the

base-rim c' of the body C. The sheet-metal casing A, which is of cylindric form, is slightly larger in diameter than the downwardly-extending rim or flange b of the bottom, and is slipped down over and around the same and to a bearing upon the base-rim c' of the bottom body or frame. The parts which are thus combined are secured together permanently by rivets a, which are preferably inserted through the circular portion c of the bottom body or frame C, the rim b of the bottom, and the cylindric casing A, as is shown in Fig. 1.

In lieu of rivets the sheet-metal bottom may be secured on its body or frame, and the casing A may be soldered thereto; or the parts may be secured together by both rivets and solder. When the invention is applied to an ash-can, as shown in Figs. 1 and 2, the casing or body A may be provided with handles A.

Referring now to Fig. 3, which represents a stove such as is used by confectioners, D designates the fire-pot, and D' the ash-pit, which are separated by a grate, C'. This grate C' is mounted and capable of tilting in a grate-ring, C², which is secured to the body or casing A of the stove. The fire-pot D has a fire-brick lining, d, and from it extends a stove-pipe connection, d', through which the products of combustion escape. The top of the stove A² is shown as consisting of concentric rings, which provides for forming a pot-hole of a size to suit any vessel which may be placed on the stove, and which also affords an opening 85 through which fuel may be introduced. Access is had to the ash-pit through the door d².

When the invention is embodied in a confectioner's stove, I prefer to form openings e around the circumference of the bottom, and which extend through the circular portion c of the bottom body, C, and also through the flange b of the bottom B, and through the cylindric casing A. These holes e provide for free ventilation below the bottom of the stove 95 and serve to prevent the sheet-metal bottom and its supporting body or frame from becoming too highly heated.

By my invention I provide for connecting the bottom and casing of a stove, ash-can, or other cylindric vessel in a very secure manner, and the rim c' of the bottom body or frame, against which the casing and flange b and bottom abut, protects their lower edges and prevents the

stove or vessel from being indented or injured when rolled about.

I have here shown the bottom B as flat, and of course the frame or body is correspondingly flat. Both the bottom and frame or body might, however, be concave or convex.

I am aware that it is not new to construct cylindric vessels with a downwardly-flanged bottom, a cylindric casing fitting outside the same, and a ring upon which the downwardly-turned flange or rim of the bottom is slipped, and which has a shoulder against which the end of the casing abuts. Such a construction is shown in patent to T. M. Bell, No. 111,302, dated January 31, 1871, and is not included in my invention. In my improved vessel the skeleton base-frame C extends beneath the horizontal portion of the bottom B and serves to sustain and hold up the same, in addition to its function in preserving the circular form of the rim b and the casing A.

What I claim as my invention, and desire to secure by Letters Patent, is—

1. In a stove, can, or other cylindric vessel, the combination of the following parts: a sheet-metal bottom, B, having a downwardly-turned rim, b, a cast-metal skeleton base-frame, C,

which extends beneath the horizontal portion of the bottom B, and which has a circular exterior on which the rim b is slipped, and an outwardly-projecting base-rim, c', at the lower end of the circular exterior, and the cylindric casing A, fitting outside the rim b of the bottom and abutting against the base-rim c', all substantially as herein described, whereby the skeleton base-frame C serves both to support the horizontal portion of the bottom B and to preserve the cylindric form of the rim b and casing A.

2. In a stove, the combination, with a sheet-metal bottom, B, having a downwardly-turned flange, b, of a cast-metal body or frame, C, over which the flange b is slipped, and which is provided with a base-rim, c', and a casing, A, fitting outside the flange b and abutting against the rim c', the stove being provided with holes or openings e, which serve to ventilate the space below the raised bottom, substantially as herein described.

THOS. BURKHARD.
